(57) **CLAIM**

The ornamental design for an upright vacuum cleaner handle portion, as shown and described.

DESCRIPTION

FIG. 1 is a front perspective view of an upright cleaner handle portion which embodies our design;

FIG. 2 is a front view thereof;

FIG. 3 is a left side view thereof;

FIG. 4 is a right side view thereof; and,

FIG. 5 is a bottom view thereof.

The details shown in broken lines form no part of the claimed design.
